CLAIM

(21) Appl. No.: **29/198,553**

The ornamental design for an computer desk for a flip-up flat screen monitor, as shown and described.

(22) Filed: **Jan. 30, 2004**

DESCRIPTION

(51) LOC (8) Cl. **06-03**

FIG. 1 is a front, off-angle, perspective view of one embodiment of a computer desk for a flip-up flat screen monitor incorporating the new design with the flip up panel in the closed position;

(52) U.S. Cl. **D6/425**; D6/480

FIG. 2 is a front, off-angle, perspective view of the computer desk of FIG. 1 with the flip up panel and flat screen monitor in the raised position;

(58) Field of Search ..... D6/480—489, 495—499,

FIG. 3 is a front elevation view of the computer desk of FIG. 1 with the flip up panel in the closed position;

D6/429—431, 425, 511, 477, 422, 428; 108/150,

FIG. 4 is a rear elevation view of the computer desk of FIG. 3;

153.1, 11, 13, 14, 156, 157.1, 161, 50.01,

FIG. 5 is a left side elevation view of the computer desk of FIG. 3;

50.02, 65, 69, 77, 79, 83, 86; 248/188,

FIG. 6 is a right side elevation view of the computer desk of FIG. 3;

188.1, 188.8; 312/223.3

FIG. 7 is a top plan view of the computer desk of FIG. 3;

FIG. 8 is a bottom plan view of the computer desk of FIG. 3;

FIG. 9 is a front elevation view of the computer desk of FIG. 1 with the flip up panel and flat screen monitor in the raised position;

FIG. 10 is a rear elevation view of the computer desk of FIG. 9;

FIG. 11 is a left side elevation view of the computer desk of FIG. 9;

FIG. 12 is a right side elevation view of the computer desk of FIG. 9;

FIG. 13 is a top plan view of the computer desk of FIG. 9; and,

FIG. 14 is a bottom plan view of the computer desk of FIG. 9.
